UNITED STATES PATENT OFFICE.

JOSEPH PIETZUCH, OF CINCINNATI, OHIO.

DESIGN FOR A SHOE HEEL.

Application filed September 7, 1920. Serial No. 408,790. Term of patent 14 years.

To all whom it may concern:

Be it known that I, JOSEPH PIETZUCH, a citizen of the United States of America, and a resident of the city of Cincinnati, in the county of Hamilton and State of Ohio, have invented a new, original, and ornamental Design for a Shoe Heel, of which the following is a specification, reference being had to the accompanying drawing, forming part thereof.

In the drawing:

Fig. 1 is a perspective view of a shoe heel, embodying the new design, and Fig. 2, is a side view thereof.

I claim:

The ornamental design for a shoe heel, as shown.

Witness my hand at the city of Cincinnati, in the county of Hamilton and State of Ohio, this 1st day of Sept., 1920.

JOSEPH PIETZUCH.
